UNITED STATES PATENT OFFICE.

BERNARD ELSHOFF, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

ALTERNATING-CURRENT DYNAMO-ELECTRIC MACHINE.

No. 925,884.

Specification of Letters Patent.

Patented June 22, 1909.

Application filed November 20, 1906. Serial No. 345,601.

To all whom it may concern:

Be it known that I, BERNARD ELSHOFF, citizen of the United States, residing at Norwood, in the county of Hamilton and State of Ohio, have invented certain new and useful Improvements in Alternating-Current Dynamo-Electric Machines, of which the following is a full, clear, and exact specification.

10 My invention relates to dynamo-electric machines and particularly to alternating current induction motors.

It is desirable for the best running conditions of induction motors that the resistance of the closed secondary windings be very low. The low resistance is not advantageous, however, for starting, owing to the fact that the currents induced in the secondary windings are so large that they react upon the field and greatly weaken the same, giving a very low starting torque. If a resistance is inserted in the secondary windings upon starting, the strength of the induced currents is correspondingly reduced 20 and an effective starting torque is obtained. It is therefore common to insert resistance in circuit with the secondary windings on starting, and to cut this resistance out gradually as the motor comes up to speed. In 25 this manner the requirements for best starting and running conditions are fulfilled.

In some types of machines the starting resistance is arranged external to the rotor and is connected to the secondary windings 30 by means of brushes bearing upon collector rings which are carried by the rotor and are electrically connected to the secondary windings. In such machines, means are provided for short-circuiting the secondary 35 windings after the rotor is up to speed. This is usually accomplished by means of a short-circuiting switch arranged at the end of the machine for connecting together the collector rings.

40 In order that the resistance of the short-circuiting device may be as low as possible it is necessary that large contact members be provided in the short-circuiting device and that the surfaces of contact be held very 45 tightly in engagement with one another.

The movable contact member of the short-circuiting switch is usually controlled by

one or more levers extending outward from the end of the machine.

Generally the actuating device is large, 55 cumbersome, occupies considerable space and requires the expenditure of considerable manual energy to shift the short-circuiting switch from one position to another.

One of the objects of my invention is to provide means for operating the short-circuiting switch and for obtaining adequate pressure between the movable and stationary contact members without requiring the expenditure of as much energy as heretofore 60 required.

A further object is to so construct and arrange the actuating mechanism of the short-circuiting device that the machine is considerably shortened and hence less floor 70 space required.

My invention consists in novel details of construction and combinations and arrangements of parts described in the specification and set forth in the appended claims.

For a better understanding of my invention, reference is had to the accompanying drawings in which—

Figure 1 is an elevation of an alternating current induction motor equipped with my invention; Fig. 2 is an enlarged section of the parts at the collector ring end of the shaft showing the short-circuiting mechanism; Fig. 3 is a vertical section taken approximately along the line 3—3 of Fig. 2, 80 looking in the direction of the arrow; Fig. 4 is a partial section taken along the line 4—4 of Fig. 2, looking in the direction of the arrow; and Fig. 5 is a view similar to Fig. 2 showing a slight modification.

Referring now to the figures of the drawing, 10 represents a casing of an induction motor having end members 11 and 12, provided with bearing housings for the shaft 13 which carries the rotary member. At 14, 15 and 16 are shown three slip rings or collector rings. These rings are secured, by insulated bolts 17, to a ring or collar 18 mounted on the end of the shaft so as to leave considerable space within the collector rings. The collector rings are separated from one another and from the ring or collar 18 by suitable insulation 19. The portions of the collector rings through which the

bolts 17 pass are slightly enlarged, as shown at 20 in Figs. 2, 4 and 5, and each ring is also provided with an inwardly extending lug 21, shown in the same figures. Secured to the lugs 21 of the collector rings are cables 22 which pass through an opening in the shaft and are connected to the secondary windings (not shown). The ring or collar 18 is provided with a cross piece 23 bridging the opening for the shaft. This bridging piece may be integral with the collar or may be a separate piece secured thereto.

Located just beyond the collector ring 14 and separated therefrom by insulation 19 are three sector-shaped plates 24, 25 and 26 separated from one another by radial insulating partitions 27. Located on the outer side of the sector plates is an insulating ring or washer 28 and beyond the ring or washer is an end-plate 29. All these parts are tightly clamped together in this case by the bolts 17 which clamp the collector rings to the supporting ring 18. If desired however the end plate 29 may be secured in position by separate bolts or screws independently of the bolts 17 so that said plate can be removed without disturbing the other parts. The plates 24, 25 and 26 are made of good conducting material and are each provided with an inner flange 30 which is beveled on its inner face. These plates form contact members of the short-circuiting switch which are fixed relatively to the shaft and rotary element of the machine, each plate being electrically connected to one of the collector rings, in this case by an insulated bolt or screw 31 which passes through the flange 30 of the plate and the inwardly extending lug 21 of the ring. The central portions of the plates 24, 25 and 26 and of the ring or washer 28 are cut away forming a circular opening.

The relatively movable contact member of the short-circuiting switch is shown at 32 and consists of a group of disk-shaped laminae mounted on a spool 33. The laminae are clamped together and to a plate 34 on one side of the laminae by any suitable means, such as bolts or rivets. The laminae are of gradually increasing diameters so as to form a beveled surface which may be clamped against the beveled flanges 30 of the relatively stationary contact members. The actuating or operating means for the short circuiting switch consists in this case of two sets of toggle arms 35 located entirely within the collector rings, the arms being pivoted to the plate 34 forming part of the relatively movable switch member and to the bridging cross piece 23.

In the preferred form of my invention shown in Fig. 2, each pair of toggle arms is provided with a roller 35^a mounted on the pin connecting the two arms. It is seen that when the toggle arms are straightened out

or cramped the movable switch member is moved outward and is forced into engagement with the contact plates 24, 25 and 26. Pressure is applied to the toggle joints by means of an axially movable arm or rod 36 having in this case a collar 37 within the collector rings which collar is provided with a beveled or conical portion 37^a and a cylindrical portion 37^b. The operating arm 36 is supported by the bridging member 23 and by the end plate 29 which are provided with suitable openings directly in line with the axis of the shaft. The arm is provided at its outer end with a hand piece 38 by means of which it can be moved in or out. The arm is also preferably provided with a collar 39 between the end plate 29 and the movable switch member 32 to engage the latter so as to insure the switch being opened when the arm 36 is moved inward. I have provided positive stops for the inner and outer positions of the arm 36, consisting in this case of a member 40, preferably a ball, pressed inward against the arm 36 by a spring 41. The ball and spring are located in a socket or recess in an outer lug or extension of the end plate 29, being held therein by a screw 42. The arm 36 is provided with grooves 43 and 44 so located as to receive the ball 40 when the arm has reached its inner and outer positions respectively.

It is seen that when the arm 36 is pulled outward the rollers 35^a ride up on the conical portion 37^a of the collar 37 and then on to the cylindrical portion 37^b. The arms are thus spread outward, forcing the movable switch member tightly into engagement with the relatively stationary switch members. It will also be seen that comparatively little pressure applied to the toggle joints causes a very great pressure at the outer ends of the toggle arms or between the contact faces of the switch. The action of centrifugal force tends to close the switch, thus lessening the energy necessary to be expended by the operator in short circuiting the windings. Furthermore centrifugal force assists in maintaining the switch closed so that there is little danger of the windings being open-circuited during the operation of the machine. When the switch is closed, since the rollers rest on the cylindrical portion 37^b of the collar, there is no tendency for it to open. In this position of the arm the ball 40 lies in the groove 44 and prevents the switch being accidentally opened. To open the switch the arm 36 is pushed inward, permitting the rollers 35^a to ride down the beveled portion 37^a of the collar 37. The switch member 32 is then engaged by the collar 39, positively forcing the former away from the contact plates in case for any reason the switch should not open when the arm 36 is pushed inward. It is seen also that the actuating mechanism is located entirely within

the collector rings and therefore does not add to the length of the machine.

In Fig. 5 I have shown a slight modification of my invention. In this case each pair 5 of toggle arms 35¹ are connected to the arm 36¹ by links 45 which are pivoted to the toggles and arm. With this construction the toggles are moved positively inward and outward by the arm 36¹. When the switch 10 is closed the links 45 are almost in a line so that there is little tendency for the switch to open due to the pressure between the contact faces of the switch. The arm 36¹ may be provided on each side of the bridging 15 piece 23 with means such as collars 46 and 47 to prevent excessive movements of the arm 36¹.

It is evident that my invention may be modified considerably in the minor details 20 without departing from its spirit and scope and I aim in my claims to cover all such modifications.

What I claim as new and desire to secure by Letters Patent is:—

25 1. In an alternating current motor, a shaft, a plurality of collector rings, means for short-circuiting said rings comprising contacts fixed relative to the rings and conductively related thereto, an axially movable contact 30 adapted to engage said relatively fixed contacts, and means for shifting the axially movable contact, comprising a toggle mechanism connected thereto and located within the rings, and a manually movable device in 35 operative relation to the toggle mechanism.

2. In an alternating current motor, a shaft, a plurality of collector rings, a short circuiting device therefor comprising a plurality of contact members fixed relative to 40 the rings and conductively related thereto, and a contact member movable with respect to the rings, and adapted to engage the relatively fixed contact members, a toggle mechanism for shifting said movable contact member, and an axially movable rod in line with 45 the center of the shaft and in operative relation to the toggle mechanism for controlling the latter.

3. In an alternating current motor, a shaft, 50 a plurality of collector rings, means for short circuiting said rings comprising contact members electrically connected to the rings and fixed relative thereto, a contact member movable relative to the rings, a toggle mechanism for forcing said relatively 55 movable contact member into engagement with the relatively fixed contact members, said toggle mechanism being located within the rings, and means for actuating the toggle 60 mechanism comprising a longitudinally mov-

able rod in line with the center of the shaft and in operative relation to the toggle mechanism.

4. In an alternating current motor, a plurality of collector rings, a short circuiting 65 device therefor comprising a plurality of contact members fixed relative to the rings and conductively related thereto, and an axially movable contact member, a toggle mechanism for shifting said axially movable 70 contact member, and an axially and longitudinally movable rod in operative relation to the toggle mechanism for controlling the latter.

5. In an alternating current motor, a shaft, 75 a plurality of collector rings, and means for short circuiting said rings comprising contact members fixed relative to the rings and connected thereto, and a coöperating axially movable contact member, a toggle mechanism 80 connected to said axially movable contact member, and a longitudinally movable rod passing loosely through said axially movable contact member, in line with the center of the shaft, and in operative relation 85 to the toggle mechanism.

6. In an alternating current motor, a shaft, a plurality of collector rings, and means for short circuiting said rings, comprising a plurality of contact members fixed relative 90 to the rings and connected thereto, and a co-operating axially movable contact member located beyond the end of the shaft and within said rings, a toggle mechanism also located within the rings and connected to said 95 axially movable member, and an axially movable rod in operative relation to the toggle mechanism, said rod being supported beyond the end of the shaft in line with the center thereof and passing loosely through 100 said axially movable contact member.

7. In an alternating current motor, a shaft, a plurality of collector rings, means for short circuiting said rings comprising contact members fixed relative to the rings and 105 connected thereto and a coöperating axially movable contact member, a toggle mechanism connected to said axially movable contact member, and a longitudinally movable rod in operative relation to the toggle mechanism and supported in line with the center 110 of the shaft, said axially movable contact member being slidably mounted on said rod.

In testimony whereof I affix my signature, in the presence of two witnesses.

BERNARD ELSHOFF.
